UNITED STATES PATENT OFFICE.

SUSANNAH M. FREILEWEH, OF POUGHKEEPSIE, NEW YORK.

SUITCASE.

Application filed July 14, 1921. Serial No. 484,701.

To all whom it may concern:

Be it known that SUSANNAH M. FREILEWEH, a citizen of the United States, residing at 412 Church Street, Poughkeepsie, in the county of Dutchess and State of New York, has invented certain new and useful Improvements in Suitcases, of which the following is a specification.

This invention relates to new and useful 10 improvements in traveling-cases, and more particularly in that type of traveling cases commonly known on the market as "dress suit" cases, and is especially designed as an improvement in the construction shown in 15 Patent No. 758,170 of April 26, 1904.

In the accompanying drawings, which are for illustrative purposes only and are therefore not drawn to scale:—

Fig. 1 is a perspective view of a dress-suit 20 case constructed in accordance with my invention, the cover or lid of the same being partially raised to more clearly illustrate the construction.

Fig. 2 is a transverse section taken 25 through the same, the cover being in its closed position.

Figure 3 is a fragmentary sectional view of a corner portion of the case made on an enlarged scale.

Figure 4 is a fragmentary perspective 30 view of the inner part of the case detached from the outer part thereof.

Figure 5 is a transverse sectional view of the upper edge portion of the body of the 35 case.

Referring to the drawings for a more particular description of the invention and in which drawings like parts are designated by like reference characters throughout the

40 several views, the numeral 1 represents a dress suit case of the usual form, comprising a rectangular body or box 2 having an open top or face adapted to be closed by a hinged cover or lid 3. The sides and ends,

45 4 and 5, respectively, of the body 2 are, as shown, constructed of outer and inner layers or thicknesses 6 and 7 of suitable material, between which, adjacent to their upper edges, is interposed an intermediate rec-

50 tangular re-inforcing frame 8 of sheet metal. The metal frame and inner layer of the suit case body project above the upper edge of the outer layer, and are bent inwardly, as at 9, to form a surrounding inclined edge 10 for the open top or face of the body. The metal frame may extend down to any de-

sired extent between the inner and outer layers of the suit case frame and the three layers secured together in any suitable manner. It will be seen that the metal re-inforcing frame forms an exceedingly durable and rigid rim for the open top or face of the body and that the down-turned edges 11 of the hinged cover or lid 3 rest securely upon said beveled rim to provide a simple and effective closure for the case.

In carrying out the present invention, the metal reinforcing frame is made in one single continuous piece, the metal being crimped at the corners, as at 12, in forming 60 the inwardly bent projecting portion. It will also be noted that the rivets 13 which secure the hinges 14 for the cover as well as the handle 15 in place, extend through the metal re-inforcing frame, whereby the lid 65 and handle are securely held against pulling out, as is now frequently the case.

The inner layer 7 of the suit case body is recessed, as at 16, to receive the hinges 14. Thus the rivets will only extend through 70 the hinges and metal re-inforcing frame 8 and the hinges will be countersunk or disposed with their inner faces flush with that of said inner layer, as shown more particularly in Figure 2.

The edges of the inner leaves of the hinges abut against the edges of the recesses and thus the hinges are braced in their positions upon the frame 8. The knuckles of the hinges are housed in the recesses and the inward bend or angle 9 prevents articles of clothing contained within the body of the case from catching in the knuckles of the 80 hinges.

From the foregoing description taken in 95 connection with the drawings, it is thought that the construction, operation and advantages of my invention will be readily understood without requiring a more extended explanation.

Having described my invention, what I claim as new and desire to secure by Letters 100 Patent, is:—

A suit case comprising a body having a bottom portion and four wall portions, a 105 continuous reinforcing frame of sheet metal secured to the inner surface of the walls of the body and projecting above the upper edges thereof, said projecting portions being inwardly inclined at the line of the upper edges of the walls of the body, a lining applied to the inner surface of the reinforce-

ing frame and lying against the inclined portions thereof, a lid having edge walls adapted to receive the inclined portions of the reinforcing frame and the lining and rest 5 upon the upper edges of the walls of the body, hinges having leaves secured to the inner surface of one of the edge walls of the lid, the lining having recesses which snugly receive the other leaves of the hinges, securing 10 devices connecting the last mentioned leaves of the hinges with the reinforcing frame, the said recesses being extended into the lining at the adjacent inclined portion thereof and the adjacent inclined portion of

the reinforcing frame having recesses which 15 register with the upper portions of the first mentioned recesses and through which the leaves of the hinges which are attached to the lid may swing and the articulated joint between the leaves of the hinges lying between the opposite edges of the said recesses and substantially at the upper edges of the walls of the body and at the angles of inclination of the said inclined portions. 20

25 In testimony whereof she affixes her signature.

SUSANNAH M. FREILEWEH.
